COMPOSITION FOR USE IN LAUNDERING

Silas M. Ratzkoff, Philadelphia, Pa., assignor to
 Publicker Research and Development Company,
 Philadelphia, Pa., a corporation of Pennsylvania

No Drawing. Application July 30, 1932,
 Serial No. 627,167

6 Claims. (CL. 8-2)

My invention relates to the art of cleansing fabrics and more particularly to the neutralization and removal of alkaline substances and soaps in the course of laundering operations.

5 My process is primarily concerned with the laundering step which is commonly considered under the designation of "souring" and in connection with which in the prior practice it has been customary to use free acids, such, for example, as oxalic acid and acetic acid. In lieu of oxalic acid or acetic acid, acid salts have also been used. The use of acids or acid salts, while functioning to neutralize the alkaline content in the fabrics, is nevertheless undesirable because 10 of the fact that such materials injure the fabrics. This is especially so due to the fact that it is impossible to add just the precise amount of acid or acid salt required to just neutralize the alkaline constituents present. Furthermore, such acids or acid salts cause a stiffening and consequent weakening of the fabric with the result that the life of the fabric is 15 greatly reduced by such laundering agents. Further, in connection with such souring treatments, discoloration or staining of the fabrics often is a consequence. Also, many of these souring agents possess the disadvantage that they are difficult to rinse from the fabric and their persistence causes trouble in the further 20 processing of the goods, such for example, as in the subsequent starching, bluing, or sizing operations. The difficulties and troubles incident to the use of such souring agents as have been used in the past have been copiously discussed, 25 for example, in the Manual of the National Laundrymen's Association.

I have found that by a particular choice of 30 agents, the alkaline and soap content of fabrics present after the cleansing step can be neutralized without incurring the difficulties and disadvantages incident to the use of such souring materials as have to my knowledge been used in the past. For this purpose I have found that simple neutral salts of weak bases and strong 35 acids, capable of hydrolysis, especially in warm water, restricted to such simple salts as are colorless and water soluble, and further restricted to such simple salts whose positive radical will react to form colorless stearates, 40 oleates, palmitates, or homologs occurring in soaps or other cleansing agents including phosphates. The metallic or positive radical of the simple neutral salt consists of such metal from groups II, III, or IV of the Periodic Table as will 45 answer the above requirements of forming color-

less water soluble sulfates, nitrates, and halides, and colorless and preferably insoluble stearates and oleates. The preferred metals from these groups are magnesium, zinc, cadmium, and aluminum. Of possible but less desirable usage 5 than these metals are beryllium, gallium, thallium, germanium, and tin. The negative component of my reagent may be derived from any of the strong mineral acids and may be a nitrate, halide, or sulfate radical, for example. The materials which I specifically prefer as my neutralizing agents are magnesium, zinc, and aluminum salts of strong mineral acids; however, I appreciate, as above set forth, that numerous other materials may be used in place of these particular materials with similar or comparable results.

10 My reagents have the particular advantage that they are neutral, and therefore excesses of my reagent in the fabric do not have deleterious effects as do excesses of acid such as are encountered when the acid or acid salt is employed. Hence, excesses of my reagent may be readily employed without scruple or fear of injuring the fabrics in carrying out a commercial or other laundry operation, thus avoiding the 15 meticulous control necessary where acid or acid salts are used for souring. My reagents, which, as stated, are capable of hydrolysis, particularly 20 in warm water, possess the characteristics of being stoichiometrically neutral when in solution, but in the presence of alkaline materials, the strong acid radical of my reagent reacts to neutralize the alkaline materials, leaving the corresponding weak basic radical of my reagent to join with the negative radical associated with 25 the alkaline or basic substance which it was sought to neutralize. In other words, the neutral 30 salts, which I employ possess the property of dissociating and reacting with alkaline constituents present just so far as is necessary to 35 neutralize the alkaline material present. When such alkaline material is neutralized, any excess of my reagent which remains is neutral and readily water soluble, so that it has no deleterious effect on the fabric and is easily rinsed 40 therefrom.

45 In a laundering operation, treatment with my agent will normally come after the fabric has been washed with soap or other alkaline material, and preferably after such washed fabrics 50 are rinsed with water to remove the bulk of the soap or alkali present. However, it may follow any other operations in the preparation or laundering of fabrics, such as bleaching, if such are conducted under alkaline conditions. 55

The amount of my agent required to bring about the decomposition or neutralization of alkaline material or soap can readily be determined by a rough titration of a sample of 5 the water solution, which is in contact with the fabrics, with a standard acid or with a standard solution of one of my agents herein disclosed for the purpose of neutralization. Phenolphthalein will serve as a suitable indicator. In lieu of titration, one or more of my agents may be added directly, a portion of a time, taking a sample of the liquid after the addition of each portion and adding a few drops of phenolphthalein thereto. If the indicator turns pink, more agent is required for neutralization. But when on test the indicator remains colorless, sufficient of my neutralizing agent has been added. After use of my agent for a time, being familiar with laundering operations, the approximate quantity of agent required will ordinarily be known in advance, thus minimizing the difficulty of the test or even eliminating the need for a test. If aluminum sulfate, for example, is the agent employed, it 15 may be roughly stated that approximately $\frac{1}{4}$ pound of agent per hundred pounds of wash will normally be required; or about one teaspoonful of agent will be sufficient for the average household wash. However, as explained above, 20 excesses of agent do not harm the fabrics, because of the chemical neutrality of the agent, and are readily rinsable from the fabrics. The principal objection to the addition of a large excess of agent is the attendant unnecessary 25 waste of agent.

In the appended claims the term "alkaline material" contemplates all laundering agents which give an alkaline reaction when in water solution, including the so-called neutral soaps.

40 What I claim is:

1. In the art of laundering fabrics which have been subjected to a washing operation with an aqueous solution of an alkaline cleansing agent, the method for neutralizing alkaline materials 45 remaining in association with such fabrics subsequent to said washing operation which comprises bringing said fabrics into contact with a water solution of a simple neutral salt of a weak metallic base and a strong acid.
2. In the art of laundering fabrics which have been subjected to a washing operation with an aqueous solution of an alkaline cleansing agent, the method for neutralizing alkaline materials remaining in association with such fabrics subsequent to said washing operation which comprises bringing said fabrics into contact with a water solution of a simple neutral salt whose positive radical is chosen from the metals of

groups II, III, or IV of the Periodic Table, which radical is capable of forming colorless and water soluble salts with the negative radical of a strong mineral acid and which forms colorless salts with radicals of fatty acids, and whose negative radical is taken from one of the strong mineral acids.

5

3. In the art of laundering fabrics which have been subjected to a washing operation with an aqueous solution of an alkaline cleansing agent, the method for neutralizing alkaline materials remaining in association with such fabrics subsequent to said washing operation which comprises bringing said fabrics into contact with a water solution of a simple neutral salt whose positive radical is chosen from the group of metals comprising aluminum, magnesium, zinc, cadmium, beryllium, gallium, thallium, germanium, and tin, and whose negative radical is chosen from a strong mineral acid to provide 15 a colorless and water soluble salt.

10

4. In the art of laundering fabrics which have been subjected to a washing operation with an aqueous solution of an alkaline cleansing agent, the method for neutralizing alkaline materials 20 remaining in association with such fabrics subsequent to said washing operation which comprises bringing said fabrics into contact with a water solution of a simple neutral salt whose positive radical is chosen from the group of metals comprising aluminum, magnesium, zinc, and tin, and whose negative radical is chosen from among the strong mineral acids to provide a salt 25 which is colorless and readily soluble in water.

30

5. In the art of laundering fabrics which have been subjected to a washing operation with an aqueous solution of an alkaline cleansing agent, the method for neutralizing alkaline materials remaining in association with such fabrics subsequent to said washing operation which comprises bringing said fabrics into contact with an aqueous solution of a simple neutral salt whose positive radical is chosen from the group of metals comprising aluminum, magnesium, zinc, cadmium, beryllium, gallium, thallium, and germanium, and whose negative radical is chosen from a strong mineral acid to provide a color- 40 less and water soluble salt.

40

6. In the art of laundering fabrics which have been subjected to a washing operation with an aqueous solution of an alkaline cleansing agent, the method for neutralizing alkaline materials remaining in association with such fabrics subsequent to said washing operation which comprises bringing said fabrics into contact with an aqueous solution of a simple neutral aluminum salt of a strong mineral acid.
